UNITED STATES PATENT OFFICE.

HENRY HEBERT, OF FALL RIVER, MASSACHUSETTS, ASSIGNOR TO
DRAPER COMPANY, OF HOPEDALE, MASSACHUSETTS, A COR-
PORATION OF MAINE.

MEASURING MECHANISM FOR WARPERS.

SPECIFICATION forming part of Letters Patent No. 737,405, dated August 25, 1903.

Application filed July 12, 1902. Serial No. 115,294. (No model.)

To all whom it may concern:

Be it known that I, HENRY HEBERT, a citizen of the United States, and a resident of Fall River, county of Bristol, State of Massachusetts, have invented an Improvement in 5 Measuring Mechanism for Warpers, of which the following description, in connection with the accompanying drawings, is a specification, like characters on the drawings representing like parts.

This invention has for its object the production of a simple and efficient measuring mechanism particularly adapted for use in connection with warping-machines whereby 15 the same can be automatically stopped when a predetermined length of yarn has been wound upon the beam. Devices of this general type have been heretofore constructed wherein the motive power has been derived 20 from the measuring-roll or from the winding-drum by or through which the beam is rotated, and herein I have shown my invention as relating to the former class, the motion of the measuring mechanism being derived from 25 the measuring-roll.

The various novel features of my invention will be hereinafter described, and particularly pointed out in the following claims.

Figure 1 is an end elevation of a warping-machine of usual construction with one embodiment of my invention applied thereto; and Fig. 2 is a sectional detail on the line 22, 30 Fig. 1.

Referring to Fig. 1, the winding-drum D, 35 the beam B¹⁰, on which the yarn w is wound, the measuring-roll M, detectors D¹⁰ to arrest a normally vibrating feeler (not shown) upon breakage of a warp-thread, the rock-shaft a', on which the feeler is mounted, and the de- 40 pending arm a, fast on the rock-shaft and vibrating as the shaft is rocked in usual manner, may be and are all of well-known or usual construction. The belt is shipped by or through the turning of a rock-shaft b³, hav- 45 ing an attached starting-treadle B^X and a rocker-arm b⁵, a shipper-rod b⁷ being connected at b⁶ to the rocker-arm and being upturned and extended through a holding-plate b^X, a shoulder b⁸ engaging the under side of the

plate and maintaining the stop-motion inoperative when the machine is running, substantially as in United States Patent No. 624,541, dated May 9, 1899. So, too, the upturned rocker-arm d⁴, having the pivotally-mounted latch d⁸, with its upturned arm d¹⁰ in the path of the pin a^X and provided with a toe d⁹ to enter between the shipper-rod and the knock-off lever b⁹ when the machine is to be stopped automatically, and the lug b¹⁰ of the knock-off lever may be substantially as in 60 said patent, the rotation of the drum D acting, through the cam d and follower-arm d², to rock or vibrate the arm d⁴. When the machine is running properly, the vibrating arm a prevents the toe d⁹ from coöperating with 65 the knock-off lever; but a released detector acts to stop the rotation of the rock-shaft a'. The latch d⁸ rocks, and the toe engages the knock-off lever, so that on the swing of the arm d⁴ to the left, Fig. 1, the lug b¹⁰ will act 70 upon the shipper-rod b⁷ and release it from its holding-plate to thereby stop the machine, all in well-known manner.

I will now describe the measuring mechanism.

The journal m of the measuring-roll M has secured to it a worm m' in mesh with a worm-gear m², fast on a horizontal shaft m³, rotatably mounted in bearings m^X on the warper-frame, said shaft having a worm m⁴ formed 80 thereon in mesh with a peripheral worm-gear m⁵ on a disk M'. The latter is provided with a circularly-arranged series of holes m⁶, any one of which is adapted to receive a releasing or tripping pin m⁷, and in order that I 85 may readily disengage the worm m⁴ and gear m⁵ I have rotatably mounted the disk M' on an eccentric hub m⁸ (see Fig. 2) on a stud m⁹, mounted in a suitable bracket m¹⁰, secured to the main frame. A handle m¹² is attached 90 to the outer end of the stud, and by turning the latter the eccentric hub m⁸ will act to raise or lower the disk M', so that when raised out of operative engagement with the worm m⁴ the disk can be turned in either direction 95 by hand. In Fig. 1 the arrows 20 and 30 indicate, respectively, the direction of rotation of the measuring-roll and the disk M'. A

bracket N on the frame has a guide 15 for an upright headed slide-rod n^x , provided with a collar n and having its lower end guided by a guide 16 on the main frame, the lower 5 end of the slide-rod being normally held out of the path of a lug a^{10} on the vibrating arm a by or through a detent n^2 , slidably mounted in guides 22 on an arm n' of the bracket N, a spring s, Fig. 1, acting to maintain one end 10 of the detent in position beneath the collar n. The opposite end of the detent is downturned at n^3 in the path of movement of the pin n^7 , so that when the rotation of the disk M' brings the pin into engagement with the part 15 n^8 of the detent the latter will be drawn out from beneath the collar n. The slide-rod n^x immediately descends into the path of the lug a^{10} , stopping the vibration of the arm a, and thereby effecting the operation of the 20 stop-motion mechanism for the machine, as has been described, the slide-rod acting as a stop for the arm a. Now by adopting a certain number of teeth for the gears m^2 and m^5 and the worm m^4 and providing for, say, one 25 revolution of the worm m' to move the gear m^2 ahead one tooth it will be manifest that the series of holes m^6 can be so numbered and arranged as to indicate a certain number of yards of warp wound for each hole. Then 30 adopting a starting or zero point on the disk M' and putting the pin m^7 in the proper hole (corresponding to the desired number of yards to be wound) if the disk be set at the starting-point and the machine set in operation 35 the rotation of the disk will gradually move the pin m^7 toward the depending end n^3 of the detent. When the desired number of yards have been wound upon the beam, the pin retracts the detent, and the machine is 40 stopped automatically.

The mechanism is simple, effective, and durable. It can be readily set to the desired

number of yards to be wound, and will not easily get out of order.

To reset the slide-rod n^x , the operative lifts 45 it after setting the disk or dial M', and the detent n^2 clicks past the collar n.

Having fully described my invention, what I claim as new, and desire to secure by Letters Patent, is—

1. In a warping-machine, a measuring-roll, measuring mechanism for the warp, actuating means therefor operated by the measuring-roll, and stopping means for the machine, including a normally vibrating member, the 55 measuring mechanism including a stop, a detent to maintain it out of the path of movement of said member, and adjustable means to render the detent inoperative and thereby release the stop when a predetermined length 60 of yarn has been wound.

2. In a warping-machine, stopping means, warp-measuring mechanism to effect the operation of said means when a predetermined length of warp has been wound, said means 65 including a detent, a disk having a pin to engage the detent and also provided with a gear, a driving-worm to actuate said gear, and thereby rotate the disk, and means to disengage the gear and worm to permit manual rotation of the disk to set the same, said means comprising a rotatable stud having an eccentric hub on which the disk is rotatably mounted, combined with means to actuate the driving-worm, rotative movement of the 75 stud moving the disk and its gear toward or away from the driving-worm.

In testimony whereof I have signed my name to this specification in the presence of two subscribing witnesses.

HENRY HEBERT.
